Primary Examiner — Phillip S Hyder(74) *Attorney, Agent, or Firm* — Goldstein Law Offices, P.C.(57) **CLAIM**

The ornamental design for an extraction device, as shown and described.

DESCRIPTION

FIG. 1 is a perspective view of the extraction device in full lines.

FIG. 2 is a front elevational view of the extraction device.

FIG. 3 is a rear elevational view thereof.

FIG. 4 is a top plan view thereof.

FIG. 5 is a bottom plan view thereof.

FIG. 6 is a right side elevational view thereof.

FIG. 7 is a left side elevational view thereof; and,

FIG. 8 is a second perspective view of the extraction device in conjunction with a broken line depiction of a pump housing. The broken line depiction of the pump houses is provided for purposes of environment and forms no part of the claimed design.
